UNITED STATES PATENT OFFICE

WALTER E. COPITHORN, OF NATICK, MASSACHUSETTS

ADJUSTABLE FOOT SUPPORT

Application filed September 14, 1929. Serial No. 392,508.

This invention relates to an adjustable foot support.

Foot troubles, especially those requiring arch supports, vary greatly so that a different support for each foot is often required, and oftentimes the height of the support required for the same foot varies from time to time as the foot becomes stronger or weaker.

Accordingly one of the objects of my invention is to provide a support for the foot at the arch or other parts of the foot which may be adjusted to the particular needs of each person. Another object has been to make this support comfortable and resilient for the wearer.

With the above and other objects in view which will more readily appear as the nature of the invention is better understood, the same consists in the novel construction, combination and arrangement of parts hereinafter more fully described, claimed and illustrated in the accompanying drawings.

In the drawings:

Figure 1 is a side elevation of a shoe partly in section showing two forms of my adjustable support for the arch and ball of the foot respectively.

Figure 2 is top view of the same partly broken away.

Figure 3 is a cross-sectional side view of a shoe showing the form of adjustable support preferable for supporting the arch.

Figure 4 is an enlarged sectional view of my adjuster taken on the line 4-4 of Figure 3.

Figure 5 is a sectional view of my adjuster provided with a spiral spring.

As illustrated my foot support when used to support the arch consists of an inner sole 12, which fits inside the shoe and extends from the heel to a point beyond the arch. Attached and fitted to the under side of which inner sole is a curved arch piece or backer 13 made of metal or other strong material. Beneath the arch piece 13 is a spring metal piece 14 which is fastened at one end to the heel portion of the inner sole 12 by rivets 15 which also pass through the arch piece 13. This spring piece 14 is so shaped that there is a space 16 between its middle portion and the

arch piece 13. The front end of this spring piece 14 is preferably not fastened, so that it may have a slight longitudinal movement when the user is walking. A hole is provided in said spring piece 14 in which hole the adjusting member A is held at its top portion. This adjusting member A, which fits into a hole made in the sole or bottom of the shoe, usually below the arch, is composed of a screw 18 having a head 19 which fits over said spring piece 14 and at the other end of said screw is a slot 20 to receive a screw driver.

An outer casing or skirt 21 threads on this screw 18, which skirt has a flange 22 at the top. A plug 23 screws into the lower portion of the skirt to keep water and dirt out. A supporting plate 24 extends from the front of the heel portion of the shoe to the sole so that it bridges the arch of the foot. This plate 24 is flat and preferably made of metal as it must be sufficiently stiff to support the weight of the person using it.

A hole is provided in this supporting plate 24 and the skirt 21 extends through said hole so that the under edge of its flange 22 rests on said plate 24. When it is desired to adjust the support a screw driver is inserted in the slot 20 and the screw 18 is thereby turned to move it upwardly or downwardly as desired. If the arch requires greater or higher support the screw is moved upwardly, whereas if less support is desired it is moved downwardly. Of course, it will be understood that as many adjusters may be used as are necessary by merely providing more holes in the spring piece 14 and in the sole of the shoe.

In the event that my adjustable foot support is inserted in the manufacture of the shoe the usual inner sole in the shoe takes the place of the inner sole 12.

I have shown a modification of my invention whereby a spiral spring may be used. This spiral spring 30 is more especially adapted for use when it is desired to support the ball of the foot. In this event a screw 35 is provided with a flange or shoulder 36, and a slot 39 at the outer end. Under the inner sole a metal backer 37 is fastened. One end 31 of the spiral spring 30 is fastened to this

backer 37 while the other end 32 fits into a hole made in the side of the screw. A skirt 38, interiorly screw threaded, having a shoulder 38a, is fitted into the sole of the shoe, in which skirt the screw 35 is threaded. As the screw 35 is moved upwardly by screwing, its flange 36 compresses the spiral spring 30, exerting a force upwardly on the metal backer 37 thereby raising it, and, of course as the screw 35 is moved downwardly the opposite effect is produced. The cap 40 fits into the screw 35 to keep the dirt out.

While a specific embodiment of the invention has been illustrated and described, the invention is not to be considered as limited to the particular combination and arrangement of parts as above described, except as limited in scope by the appended claim.

I claim:

20 A foot support for a shoe which has a hole in the outer sole, comprising a curved backer under the inner sole of the shoe, a spring piece under said backer and attached at one end to said backer and having a hole therein 25 in alignment with said hole in the outer sole, a supporting plate below said spring piece having a hole therein in alignment with said other holes, and an adjusting member embodying a screw and a screw-threaded skirt 30 screwed on said screw, said screw having a portion adjacent the top extending beyond the body of the screw on which the under side of said spring piece contacts, said skirt having a flange at its top portion which flange 35 rests on the upper surface of said supporting plate.
